UNITED STATES PATENT OFFICE.

RICHARD M. HOPKINS, OF NEW YORK, N. Y., ASSIGNOR TO AMERICAN DISTRICT TELEGRAPH COMPANY, OF JERSEY CITY, NEW JERSEY, A CORPORATION OF NEW JERSEY.

SIGNALING SYSTEM.

1,360,954.

Specification of Letters Patent. Patented Nov. 30, 1920.

Application filed October 20, 1916. Serial No. 126,650.

To all whom it may concern:

Be it known that I, RICHARD M. HOPKINS, a citizen of the United States of America, and a resident of New York, county of New York, and State of New York, have invented certain new and useful Improvements in Signaling Systems, of which the following is a specification.

My invention relates generally to signaling systems, and particularly to systems wherein one or more call boxes, thermostats, burglar alarms, or other transmitting devices are to cause the operation of signal giving devices in a plurality of circuits. The system is particularly applicable to fire alarm systems of large stores, warehouses, etc., where, in the event of fire, alarms are to be sounded at a large number of different points. In such systems, it is usually desirable that only a relatively small number of alarm giving devices shall be located in any one circuit; hence the occasion for the provision of a plurality of circuits for such alarm giving devices. It is desirable that the circuits shall be constantly under test, so that in case of any derangement (such for example as breaking of the circuit, or grounding of the circuit,) a trouble signal shall be given; yet in case an alarm is sounded, the several circuits of the alarm giving devices should be connected separately to the source of current supply; so that derangement of one such circuit shall not prevent operation of the other circuits, and so that there shall be ample current in each circuit for the operation of the alarm giving device thereof.

My system herein illustrated and described is particularly intended to be used in connection with signal giving devices which require relatively strong currents for their operation, as compared with the currents required for electric bells and the like, so that it is desirable that the supply of current to such signal giving devices shall be controlled by relays of a type adaptable for the handling of moderately large currents, and of a type which, for various reasons, it is not desirable to include directly in the transmitter circuit itself. The signal giving device of the application of Charles P. Pollak and myself, filed September 11, 1916, Serial No. 119,423, is an example of a type of signal giving device which is convenient for use in the system herein described.

The object of my invention is to provide a suitable signaling system for the operation of one or more signal giving circuits containing signal giving devices requiring an operating current of somewhat greater strength than that ordinarily required by electric bells and the like, and to provide for the automatic continuous testing of the signal giving circuits in a simple manner and by means of relatively small testing currents.

I will now proceed to describe my invention with reference to the accompanying drawings, and will then point out the novel features in claims. In said drawings:

Figure 1 is a diagram illustrating my invention, the break wheel and contact pen of the relay B being omitted to avoid confusion of illustration; and Fig. 2 is a fragmentary diagram, on a larger scale, showing means for transmitting a signal to a central station in the event of trouble occurring in the transmitter circuit.

Referring first to Fig. 1: V and G designate, respectively, incoming and outgoing current leads, T designates a transmitter circuit, one side of which is connected to V and the other side to G. T¹ designates transmitters, diagrammatically illustrated, included in the circuit T. These transmitters may be of any suitable type. Conveniently, they may be ordinary hand-operated call boxes, connected in series in the circuit T, and of a type which, in operating, successively break and close the circuit T so as to transmit a distinct signal; but they may also be automatically released, or automatically operated, transmitters of well known type, for example, transmitters which are thermostatically controlled, or thermostatically operated.

Included in the circuit T are a main relay A, and a delay action or time relay B.

F¹, F², F³ and F⁴ designate respectively circuits for alarm giving devices, which devices are designated by character F. C is a relay, preferably of the solenoid type, which operates contacts controlling circuits F¹, F², F³ and F⁴. D¹—D⁴ are relays controlling the trouble signal hereinafter mentioned.

Transmitter circuit T starts from current supply lead V, passes through the magnet of relay A, and thence through the transmitters T¹ in series and through the magnet of relay B to return current lead G. Normally, this

circuit is complete, and therefore the magnets of relays A and B are energized. When the magnet of relay A is deenergized, said relay closes a circuit from current lead V through conductor 1, the solenoid magnet of relay C, conductor 2, normally closed contact s^1 of relay B, conductor 3, the armature and back contact of relay A, and conductor 4 to the other current lead G. Normally each of the signal giving circuits F^1 , F^2 , F^3 and F^4 is connected in a circuit leading from current lead V through a conductor f^1 , f^2 , etc., to said circuit conductor, F^1 , F^2 , etc., and thence through the signal giving devices in that circuit to a return conductor f^5 , f^6 , etc., and so to G. These conductors f^5 , f^6 , etc., include resistances R^1 — R^2 , etc., which limit the current flowing normally through circuits F^1 , F^2 , etc., to a value insufficient to operate signal devices F, and sufficient only for testing purposes. From between each conductor F^1 , F^2 , etc., and its return lead f^5 , f^6 , etc., there is a shunt wire a^1 , a^2 , etc., leading to a corresponding normally open contact c^1 , c^2 , etc., of relay C, and thence to the return side of the corresponding signal giving circuit F^1 , F^2 , respectively. It will be apparent that when the solenoid magnet of relay C is energized, upon deenergization of magnet of relay A, as before explained, signal giving circuits F^1 , F^2 , etc., will all be connected in multiple to current leads V and G, through shunts a^1 , a^2 , etc., whereby resistances R^1 , R^2 , etc., are shunted out, so that current of strength sufficient to operate signal devices F will then flow through said circuits.

Test relay D^1 is permanently connected from the return side of circuit F^1 through conductor f^5 to current lead G. Relay D^1 operates a contact d^1 in a circuit 5—6 leading through a current generator 7 and trouble signal device 8. It will be clear that a break or ground in the circuit F^1 or interruption of the current supplied to that circuit, will cause relay D^1 to close circuit 5—6, so operating the trouble alarm 8. Similarly, relay D^2 is included in circuit F^2 , and in the event of a break, short or ground in that circuit will close circuit 5—6 so operating trouble signal device 8. Relays D^3 and D^4 are similarly connected in circuits F^3 and F^4 , and, through a circuit 9—10, also leading through generator 7 and trouble signal device 8, will cause the operation of that trouble signal device in the event of a break, short or ground in said circuits F^3 or F^4 . The signal giving circuits F^1 — F^4 are, therefore, normally under test.

From the foregoing it will be clear that in case one of the transmitters T^1 operates the magnet of relay A will be deenergized and reenergized successively, the solenoid magnet of relay C will be energized and de-energized successively and current of suf-

ficient strength to cause the operation of the signal giving devices F of the various circuits F^1 , F^2 , F^3 and F^4 will pass intermittently through such circuits, so operating those signal giving devices. But the magnet of relay A will also be deenergized in the event of a break in circuit T; in which case if means were not provided to prevent, the various signal giving devices F would operate continuously. In general, this is not desirable, hence the provision of relay B. When the magnet of relay B is deenergized, its armature rotates clockwise under the influence of a weight 11, and an arm 12 of that armature closes contact s^2 of that relay, thereby closing a circuit which includes generator 7 and trouble signal device 8. This closing of contact s^2 will occur even when, in normal operation, one of the transmitters T^1 is sending a signal; but in such normal operation the arm 12 does not rise far enough to open contact s^1 , for, as above stated, relay B is a delay action or time relay, and the clockwise motion of its armature is retarded by a ratchet-driven gear train 13 and fan 14. But in the case of a break in circuit T the deenergization of the magnet of relay B continues for a sufficient time, so that the arm 12 opens contact s^1 , thereby deenergizing the solenoid magnet of relay C, causing the contacts c^1 , c^2 , etc., of that relay to open, and so stopping the operation of the various signal giving devices F, though trouble signal 8 continues to operate.

When, in normal operation, one of the transmitters T^1 ceases to operate, or when in the event of development of a break in circuit T, the relay B opens its contact s^1 after a predetermined interval of time, the relay C is again restored to normal condition, so restoring to normal condition the various circuits F^1 , F^2 , F^3 and F^4 . This automatic restoration is a feature of some importance, because, in certain alarm systems now in use, the operation of the alarm-giving devices, such as devices F, in the event of development of trouble in the transmitter circuit, results in the blowing of certain fuses, or other derangement of apparatus which requires visit of an attendant and manual repair. According to my present invention, however, this is not necessary, because, as just explained, the instant the transmitters T^1 cease to operate, or the instant the relay B opens contact s^1 , the relay C is returned to normal condition automatically.

It is desirable in many cases to transmit a signal to a central station when trouble has developed. To this end a suitable break wheel and pen may be provided on the relay B. One type of alarm transmitter T^1 commonly used in the circuits of this system, comprises means for sending a signal to a central station, as well as means for operat-

ing the circuit T to cause the operation of the signal devices F. Without limiting myself to details of construction, in Fig. 2 I have indicated, diagrammatically, an arrangement of break wheels and contact pens which may be employed in such a transmitter; 15 designating the break wheel; and 16 the corresponding contact pen, for circuit T, and 17 designating the break wheel and 18 and 19 contact pens, for the central station circuit 20. I have not shown the clock train for driving these break wheels, but it may be assumed that the clock train of an ordinary call box is used for the purpose. Likewise, in Fig. 2 the break wheels are shown as of different diameters, for convenience in illustration only. It will be clear that when the transmitter to which these break wheels belong is operated, not only will break wheel 15 and pen 16 break and close the circuit T in accordance with the signal to be transmitted, but also that break wheel 17 and pens 18 and 19 will alternately break and close central station circuit 20 in accordance with the signal to be transmitted through that circuit.

Now, in order that relay B, when operated, by something other than an ordinary signal may transmit a signal through the circuit 20, that relay B is provided with a break wheel 21 and pen 22, connected in a circuit 20; this break wheel being, in the construction shown, gear-connected to the armature shaft of the relay by gears 24 and 25; and when the relay is in normal condition, the end of the pen 22 is at such distance from the beginning of the signal-toothed portion of break wheel 21, that small motions of the armature of the relay, such as are due to normal operation of the transmitters T¹, do not bring the toothed portion of the break wheel opposite the pen 22; while, on the other hand, a more prolonged motion of the armature of the relay, such as is due to a break, short or ground in the circuit T, causes the teeth of this break wheel to pass the pen 22, so sending the signal of that break wheel through the circuit 20.

It will be noted that in case of a short or ground in that portion of the circuit T which particularly contains the transmitters T¹, relay B sends a signal to central station through circuit 20 by means of its break wheel 21 and pen 22, and also, by completing its contact s₂, causes the trouble signal device 8 to operate.

It will also be seen that when a break, short or ground in such circuit T is repaired, the relay B is automatically restored, its contact s₂ being broken as a result of such automatic restoration so that no attention need be given this relay after the repair of the break, short or ground.

In another application for Letters Patent Serial No. 126,649, I have claimed means, in-

cluding the delay action relay, for stopping the operation of main signal giving devices in the event of development of trouble in a transmitter circuit controlling such signal giving devices; also means for sending a signal through a circuit other than the transmitter circuit T or the circuits F¹, F², etc., in the event of development of trouble in the transmitter circuit. Therefore such inventions are not claimed broadly herein. 75

What I claim is:—

1. In a signaling system, the combination with a source of current supply, a transmitter circuit comprising one or more transmitters, a signal-giving circuit comprising one or more signal-giving devices, means, including resistance, connecting said signal-giving circuit to the source of current supply, such resistance normally limiting the current in such signal-giving circuit to a value insufficient to operate the signal-giving device or devices therein, a trouble signal device comprising operating means normally included in such signal-giving circuit, and means, controlled by such transmitter circuit, for shunting out the said resistance when a transmitter in such transmitter circuit operates. 90

2. In a signaling system, the combination with a source of current supply, a transmitter circuit comprising one or more transmitters, a signal-giving circuit comprising one or more signal-giving devices, means, including resistance, connecting said signal-giving circuit to the source of current supply, such resistance normally limiting the current in such signal-giving circuit to a value insufficient to operate the signal-giving device or devices therein, a trouble signal device comprising operating means normally included in such signal-giving circuit, a relay included in said transmitter circuit, and switching means controlled by such relay and arranged to be operated by the relay to shunt out the said resistance when a transmitter in such transmitter circuit operates. 100

3. In a signaling system, the combination with a source of current supply, a transmitter circuit comprising one or more transmitters, a signal-giving circuit comprising one or more signal-giving devices, means, including resistance, connecting said signal-giving circuit to the source of current supply, such resistance normally limiting the current in such signal-giving circuit to a value insufficient to operate the signal-giving device or devices therein, a trouble signal device comprising operating means normally included in such signal-giving circuit, a relay included in said transmitter circuit, a second relay and a circuit therefor controlled by said first mentioned relay, said second relay arranged upon operation of said first mentioned relay to shunt out the 120 125 130

said resistance, and a delay action relay controlled by said transmitter circuit and arranged, in the event of a prolonged break or ground in said transmitter circuit, to cause 5 said trouble signal device to operate and also to nullify, as to the second relay, the effect of the operation of the transmitter circuit relay.

4. In a signaling system, the combination 10 with a source of current supply, a transmitter circuit comprising one or more transmitters, a signal-giving circuit comprising one or more signal-giving devices, means controlled by said transmitter circuit and 15 controlling said signal-giving circuit, and arranged to cause the signal-giving device or devices to operate in the event of operation of one of said transmitters, and a delay action relay included in the return end 20 of such transmitter circuit, and comprising transmitting means arranged to operate in the event of development of trouble in the transmitter circuit.

5. In a signaling system, the combination 25 with a source of current supply, a transmitter circuit comprising one or more transmitters, a signal-giving circuit comprising one or more signal-giving devices, means controlled by said transmitter circuit and 30 controlling said signal-giving circuit, and arranged to cause the signal-giving device or devices to operate in the event of operation of one of said transmitters, and a self- 35 restoring delay action relay included in the return end of such transmitter circuit, and comprising transmitting means arranged to operate in the event of development of trouble in the transmitter circuit.

6. In a signaling system, the combination 40 with a source of current supply, a transmitter circuit comprising one or more transmitters, a signal-giving circuit comprising one or more signal-giving devices, means controlled by said transmitter circuit and con-

trolling said signal-giving circuit, and arranged to cause the signal-giving device or devices to operate in the event of operation of one of said transmitters, and a delay action relay included in the return end of such transmitter circuit, and comprising transmitting means arranged to operate in the event of development of trouble in the transmitter circuit, a trouble signal device comprising operating means normally included in such signal-giving circuit, said delay action relay comprising contact means arranged to cause operation of such trouble signal means in the event of development of trouble in the transmitter circuit. 45 50 55

7. In a signaling system, the combination 60 with a source of current supply, a transmitter circuit comprising one or more transmitters, a signal-giving circuit comprising one or more signal-giving devices, means controlled by said transmitter circuit and 65 controlling said signal-giving circuit, and arranged to cause the signal-giving device or devices to operate in the event of operation of one of said transmitters, and a self- 70 restoring delay action relay included in the return end of such transmitter circuit, and comprising transmitting means arranged to operate in the event of development of trouble in the transmitter circuit, a trouble signal device comprising operating means normally included in such signal-giving circuit, said delay action relay comprising contact means arranged to cause operation of such trouble signal means in the event of 75 development of trouble in the transmitter circuit. 80

In testimony whereof I have signed this specification in the presence of two subscribing witnesses.
